UNITED STATES PATENT OFFICE.

THOMAS O. PERRY, OF OAK PARK, ILLINOIS.

HYDROTURBINE-ASPIRATOR.

1,071,789.

Specification of Letters Patent.

Patented Sept. 2, 1913.

Application filed October 10, 1910. Serial No. 586,159.

To all whom it may concern:

Be it known that I, THOMAS O. PERRY, a citizen of the United States, residing at Oak Park, in the county of Cook and State of Illinois, have invented a new and useful 5 Hydroturbine-Aspirator, of which the following is a specification.

My invention relates to improvements in hydroturbine aspirators in which a partial 10 vacuum is produced and maintained through adhesion or entrainment of the air by water or other liquid to which either actual or relative velocity is imparted by a whirling motion of the apparatus; and the objects of my 15 improvements are, first, to obtain a relative vacuum by rapid removal of air from a chamber or tube, partially or wholly closed, by means of liquid entrainment and without undue consumption or waste of the liquid used; second, to avoid the need of any 20 kind of valves, pistons, packing and strain- 25 ers such as encumber ordinary apparatus employed for maintaining vacuums; and, third, to provide for effectually intercept- 30 ing, by the entraining water or liquid, all dust with which the air may be laden.

I attain these objects by the mechanism illustrated in the accompanying drawing in which—

Figure 1 is a vertical section of the entire machine; and Fig. 2 a sectional plan of the apparatus taken below the plane indicated by the broken line 2—2 on Fig. 1.

Similar letters refer to similar parts 35 throughout the several views.

A liquid receptacle or cask A, is partially 40 filled with water as indicated in Fig. 1. Submerged in the water are two plates or disks, B, B', placed coaxially one above the other with a suitable interval between. The 45 space between these disks is divided by vertical partitions, C, C', which extend from the outer periphery toward the axis. A single bolt, D, serves to clamp the disks against the partitions. The additional short partitions, C', C', need not extend to the outer 50 periphery and are intended to act only as separators for the disks. A hollow shaft, E, connects the center of the upper disk, B, with a grooved pulley, or sheave, F, mounted just above the cask, A, in convenient position to be driven by a belt which, in turn, may be driven by a motor of any kind. The 55 sheave, F, and shaft, E, are supported and turn on a ball bearing, G, which rests on the lid, H, of the cask. This lid rests on the

annular cask head A' whose aperture is large enough to permit insertion or removal of the disks, B, B'. The pipe flanges, J, J', clamping the perforated bottom, A², of the 60 cask, serve for connecting the suction tube, K, with the central interior of the aspirator, B E' C, through the elbows, L L, coupling, M, nipples, N P Q R, and several air ducts, S, which pierce the lower disk, B', around 65 the clamping bolt D. The nipple, R, should be made of brass, or at least should have a smooth non-corrodible exterior as it forms a submerged bearing for the aspirator, which terminates below in a gland, T, which clamps 70 to the disk, B', a bushing, U, which loosely fits over and revolves around the nipple, R. If immersed in water, wood is a suitable material for the bushing, U. Water brakes, A³ A³, attached to the sides of the cask 75 reach in toward the periphery of the rotating aspirator to prevent excessive whirling of the water. The submerged suction nipple, Q, has opposite perforations, Z, closed by plugs, Z', whose heads project outwardly. 80 These plugs, Z', may occasionally be removed to admit water with the air sucked in for flushing the apparatus when cleaning becomes necessary, but they chiefly serve the purpose of furnishing a convenient hold for 85 a special wrench when it is desired to unscrew the submerged nipple from the flange, J.

The aspirating action of this apparatus is mainly due to a tangential mingling of liquid and air just within the peripheral opening between the disks, B, B', or between the divisional partitions, C, which divide the circumferential submerged space with wide intervals between. The whirling motion prevents the liquid penetrating far into the circumferential space, as, after flowing inward, through suction and its own natural pressure, behind each partition, it is immediately caught by the following partition and 90 thrown outward. Or, in the absence of dividing partitions, the liquid which gets in midway between the disks is again cast out by being whirled through adhesion between the liquid and the disks. In either case 95 100 there is a constant in and out flow of liquid in the space between the peripheries of the disks or in the outer portions of the spaces between divisional partitions. The action is enhanced by the breaking up of the liquid 105 into spray as it flows through the peripheral spaces. This entraining action of the liquid 110

is effective to produce a vacuum corresponding to 6 or 8 inches of mercury with a very moderate velocity of revolution, though the disks are submerged in water to a depth of 5 only 5 or 6 inches. The intensity of the vacuum producable depends more upon the depths of submergence than upon the rapidity of the aspirator's rotation.

While the intensity of the vacuum obtainable, in the form as shown, depends on depth of submergence rather than on speed of revolution, yet the volume of air sucked in and discharged through the water is augmented by increasing the velocity of revolution, as well as by increasing the vertical width of space between the upper and lower disks. Where it is desirable that the vacuum produced shall not exceed a certain maximum, the tension obtainable may be 10 regulated by the simple expedient of adjusting the depth, or amount, of water in the cask. The vent, V, near the top of the cask, permits the escape of air discharged through the water, if the lid, H, should fit too closely. 15 Water may be drawn off from the cask, when cleaning becomes necessary, by removing the cap from the drain nipple, W. The cask is raised a suitable distance above the ground or floor by its supports, X, 20 through one of which the suction nipple, N, passes. The suction tube, K, extends vertically above the water level of the cask, beyond which it may be extended as desired by additional piping or suction hose. As 25 the air sucked in must come in very intimate contact with water, all dust is effectually allayed and pure air only escapes 30 through the vent, V.

The efficiency of the aspirator depends 35 much upon limiting the number of partitions, C, used, or upon the circumferential width of the spaces between partitions. As many as 12 partitions have been tried, and again, all partitions have been discarded, 40 with good results, so far as producing tension in a closed chamber was concerned, but the volume of air displaced in a given time was greatly increased step by step by gradually reducing the number of partitions. 45 The best results have been obtained with 50 two partitions oppositely placed as shown.

Various modifications of construction are 55 obviously possible, and I do not confine myself to the precise form shown, although the drawing represents to a scale the apparatus substantially as actually constructed and successfully operated.

I claim:

1. The combination with a receptacle containing liquid, of axially separated submerged plates having their interposed space adapted to admit the surrounding liquid without restriction around the periphery, means for rotating said plates about their 60 common axis, partitions connecting said

plates having wide circumferential openings between adapted to receive liquid inward behind each advancing partition and to expel the liquid so received outward in front of the following partition, and a suction tube for air or gas communicating centrally with the interposed space between said plates, substantially as herein set forth. 70

2. The combination with a receptacle containing liquid, of axially separated submerged plates having their interposed space adapted to admit the surrounding liquid without restriction around the periphery only, means for rotating said plates about their common axis, partitions connecting 75 said plates having wide circumferential openings between adapted to receive liquid inward behind each advancing partition and to expel the liquid so received outward in front of the following partition, and a suction tube for air or gas communicating centrally with the interposed space between said plates, substantially as herein set forth. 80

3. The combination with a receptacle containing liquid, of axially separated submerged plates having their interposed space adapted to admit the surrounding liquid without restriction around the periphery, means for rotating said plates about their common axis, partitions connecting 85 said plates at wide circumferential intervals adapted to receive liquid inward behind each advancing partition and to expel the liquid so received outward in front of the following partition, and a suction tube for air or gas communicating interiorly with the 90 spaces and openings between said plates and partitions, substantially as herein set forth. 95

4. The combination with a receptacle containing liquid, of axially separated submerged plates having their interposed space adapted to admit the surrounding liquid without restriction around the periphery only, means for rotating said plates about their common axis, partitions connecting 100 said plates at wide circumferential intervals adapted to receive liquid inward behind each advancing partition and to expel the liquid so received outward in front of the following partition, and a suction tube for air or gas communicating interiorly with the 105 spaces and openings between said plates and partitions, substantially as herein set forth. 110

5. The combination with a receptacle containing liquid, of axially separated submerged plates having interposed space whose periphery is open to the surrounding liquid, partitions dividing the periphery of said interposed space into wide compartments, means for rotating said compartments in unison with said partitions about the central axis of the plates and a suction duct for air or gas leading to the interior of said compartments, whereby air or 120

gas may be conducted outward from between said plates to mingle with the liquid drawn inward behind each partition to be in turn expelled outward in front of each partition, 5 substantially as herein set forth.

6. The combination with a receptacle containing liquid, of submerged plates having peripheries widely separated axially, rotative partitions between said plates at wide 10 circumferential intervals, and a duct for air leading to the interior spaces between said plates and partitions, whereby liquid flowing inward behind the partitions as they rotate is in turn expelled outward in front of 15 each following partition thereby entraining and discharging air into said receptacle, substantially as herein set forth.

7. The combination with a receptacle containing liquid, of submerged plates having 20 peripheries widely separated axially, rotative partitions between said plates at wide circumferential intervals extending inward, and an air duct leading to the interior spaces between said plates and partitions, 25 whereby liquid flowing inward behind the rotating partitions is in turn expelled outwardly in front of each following partition thereby entraining and discharging air into said receptacle, substantially as herein set forth.

8. The combination with a receptacle containing liquid, of submerged plates having circular peripheries widely separated axially, rotative partitions extending inward 35 between the peripheries of said plates at wide circumferential intervals, and an air duct leading to the interior spaces between said plates and partitions, whereby liquid flowing inward behind the rotating partitions is in turn thrown outward in front of 40 each following partition thereby entraining and discharging air into said receptacle, substantially as herein set forth.

9. The combination with a receptacle containing liquid, of two or more submerged plates widely separated axially at their peripheries, rotative partitions extending inward from and dividing the circumferential space between said plates at wide intervals, 45 and an air duct leading into the interior space between said plates, whereby liquid drawn inward behind each rotating partition is in turn expelled outward in front of each succeeding partition discharging air 50 therewith into said receptacle, substantially as herein set forth.

10. The combination with a receptacle containing liquid, of submerged plates axially separated with intervening space wide

open to the liquid around their peripheries, 60 an air duct leading to the interior of said space, and rotative partitions extending inward from the peripheries of said plates dividing said intervening space into compartments of wide peripheral extent open to the 65 liquid outwardly, said compartments also having inward communication with said air duct, whereby liquid flows inward behind said rotative partitions, and in turn is expelled in front of each following partition 70 thereby entraining and discharging air into said receptacle, substantially as herein set forth.

11. The combination with a receptacle containing liquid, of submerged plates axially separated with intervening space wide 75 open around their peripheries, an air duct leading to the interior of said intervening space, and rotative partitions dividing the periphery of said intervening space oppositely into two wide peripheral compartments open outwardly to the surrounding liquid and communicating inwardly with said air duct, whereby liquid flowing inward behind and outward in front of the 80 rotating partitions entrains and discharges air into said receptacle, substantially as herein set forth.

12. The combination with a receptacle containing liquid, of an air duct leading 90 into said liquid beneath its surface, and rotative compartments operatively submerged arranged around and communicating interiorly with said air duct, said compartments also having wide peripheral openings 95 through which liquid may flow in at the leading edges and out at the trailing edges thereof, whereby air is entrained and discharged into the liquid of said receptacle, substantially as herein set forth. 100

13. The combination with a receptacle containing liquid, of submerged rotative disks or plates axially separated with intermediate space between wide open around the periphery, an air duct leading centrally 105 to the interior of said intermediate space, and radial partitions separating and connecting the peripheries of said disks on two diametrically opposite sides, whereby liquid flowing inward behind said partitions as 110 they rotate is in turn expelled in front of them thereby entraining and discharging air into said receptacle, substantially as herein set forth.
